UNITED STATES PATENT OFFICE.

CAMILLE H. BELLIVEAU, OF MONCTON, NEW BRUNSWICK, CANADA.

AUTOMATIC WINDOW WASHER.

Application filed March 3, 1926. Serial No. 92,014.

The present invention pertains to a novel automatic or mechanical window washer that requires very little manual operation and thus reduces considerably the amount 5 of time required for cleaning a window.

The principal object of the invention is the provision of a device of this character which, in addition to enabling the advantage already set forth, may be permanently installed at little expense. The device comprises essentially a window brush to which water is supplied, and mechanism for moving the brush horizontally and vertically over the window at will. In addition, a 15 special mechanism is provided for removing the brush from contact with the window when it is to be shifted from the end of one stroke to the beginning of the next stroke.

The water hose is positioned for the most 20 part at one end of the apparatus and is weighted in order to prevent tangling. Since the hose is connected directly to the window brush, the weight of the hose aids in sliding the brush horizontally towards the end of the window casing in which the 25 hose is positioned. By means of a balancing device, this effect is utilized in winding a spring, the energy of which is expended in aiding the brush to move in the opposite direction, namely, away from the end of the 30 window casing in which the hose is mounted.

The invention is fully disclosed in the following description and in the accompanying drawings in which:

Figure 1 is a vertical section of a window frame, showing the device of the invention in elevation;

Figure 2 is a horizontal section;

Figure 3 is a detail elevation of the track 40 and parts for supporting the track;

Figure 4 is a plan section corresponding to Figure 3;

Figure 5 is a fragmentary vertical section 45 at right angles to Figure 1, at the upper part of the apparatus;

Figure 6 is a section on the line 6—6 of Figure 3;

Figure 7 is a section on the line 7—7 of Figure 5;

Figure 8 is a detail vertical section at 50 right angles to Figure 1, showing the lower part of the apparatus;

Figure 9 is a fragmentary vertical section at right angles to Figure 1, showing in ele-

vation the weighted hose and associated 55 parts;

Figure 10 is a fragmentary horizontal section at right angles to Figure 1 on the line 10—10 of Figure 1;

Figure 11 is a section on the line 11—11 of 60 Figure 10;

Figure 12 is a detail elevation of the winding drum and compensating drum;

Figure 13 is a section on the line 13—13 65 of Figure 12;

Figure 14 is a section on the line 14—14 of Figure 13;

Figure 15 is a detail perspective view;

Figure 16 is a rear elevation of the window brush, the outer cover being in section; 70

Figure 17 is a vertical transverse section, partly in elevation, of the window brush;

Figure 18 is a front elevation of the window brush;

Figure 19 is a section on the line 19—19 75 of Figure 18;

Figure 20 is a section on the line 20—20 of Figure 16, and

Figure 21 is a section on the line 21—21 80 of Figure 17.

Reference to these views will now be made by use of like characters which are employed to designate corresponding parts throughout.

In Figure 1 is shown a window frame or 85 casing 1 which is divided by two horizontal partitions 2 and 3 into an upper display section 4, an intermediate compartment 5 for containing the greater part of the operating mechanism, and a lower compartment 90 6. At each end of the window-pane 7, and at the inner side thereof, is rotatably supported a worm 8 on which a nut 9 is movable. Behind each worm is rotatably mounted a guide post 10, one of the posts having a longitudinal slot 11 for the purpose pointed out below. Arms 12 extend from each nut 9 and loosely surround the adjacent post 10 as shown also in Figure 3 in order that, when the worm 8 is turned by appropriate 95 mechanism, the nut will be held from turning and will consequently slide up or down.

Each post 10 is surrounded by a slidable sleeve 13 disposed between the arms 12 from the adjacent nut. A finger 14 (Figure 3) 105 projects from the lower edge of the sleeve, and a similar finger 15 extends from a collar 16 slidably surrounding the post and mount-

ed over the upper arm 12. The two pairs of fingers 14 and 15 serve to support a pair of horizontal track members 16 (Figures 17 and 20) which are completed by vertical rails 17 secured to the ends of the tracks.

The tracks serve to support the movable window brush and appliances for supplying water thereto. Between the track members 16 is slidably mounted a header box 18 in the sides of which are journaled rollers 19 positioned between the rails 17 at each end of the tracks as clearly illustrated in Figures 16, 20 and 21. Within the box 18 is mounted a water header 20 having at one end a threaded nipple 21 (Figure 2) to which is secured one end of a water hose 22.

A bracket 23 engages the lower face of the lower track 16, and from this bracket is suspended a substantially rectangular back frame 24. The body of the window brush includes a box-like housing 25, the back 26 of which receives the free ends of screws 27 threaded through the frame 24. The back 26 may be reinforced by integral or soldered plates 28 at the points where the screws 27 penetrate. The casing 25 has a partition 29 parallel to the back and in which are formed apertures 30 near the upper edge. Rubber or similar strips 31 are laid against the vertical portions of the marginal wall 32 of the casing and secured in this position by strips 33. Additional strips 34 are secured between superposed and inclined angle irons 35 which are attached to the partition 29 by means of screws 36. The back 26 is also provided with guide pins 37 which pass through the back frame 34 as shown in Figures 16 and 17.

In the upper part of the casing 25 and behind the partition 29 is secured a header tube 38 having outlet apertures 39. Pipes 40 and 41 project rearwardly from the header 20 and tube 38 respectively and are connected by a flexible piece of hose 42. An angle piece 43 is secured to the upper side of the frame 34 and carries a horizontal roller 44 which engages one of the upper rails 17. The window brush thus described is enclosed in a cover 45 except in front of the strips 31 and 34 which are designed to engage the window-pane 7.

It will be manifest that rotation of the worms 8 raise or lower the nuts 9 whereby the tracks and window brush are correspondingly moved. In order to impart movement to the worms, a pair of spaced and aligned shafts 46 are journaled in the compartment 5 and provided at their outer ends with double pinions 47 meshing with similar members 48 carried by the lower ends of the worms. Another shaft 49 is journaled perpendicularly to the shafts 46 and is directed to the space between the shafts. The shaft 49 carries an outer operating handle 50 and is provided at its inner end with a

crown gear 51 meshing with bevel pinions 52 at the inner ends of the shafts 46. Rotation of the handle 50 turns the shafts 49 and 46 and finally the worms 8 whereby the window brush is raised or lowered in the manner already indicated.

The brush is moved horizontally across the window by a cable mechanism which is controlled from a drum 53 journaled in the lower part of the compartment 5 as illustrated in Figures 1 and 2. The shaft 54 of the drum has an exterior handle 55 for actuation. The cables 56 and 57 are wound at one end around the drum 53 and are then passed around pulleys 58 at the ends of the window frame and pulleys 60 near the lower end of each post 10. The cable 56 is passed over a pulley 61 carried by the corresponding sleeve 13 (Figure 3), and the cable 57 is passed into the slot 11, through the post 10, and over a pulley 61' carried by the track. Finally the remaining ends of the cables are secured to the header box 18 as indicated by the numerals 63 in Figure 21. As the handle 55 is turned, one of the cables is wound and the other is unwound with respect to the drum, whereby the header box, window brush and associated parts are drawn in one direction or the other along the tracks 16.

A special mechanism is provided for holding the cables taut. At one side of the drum 53 a vertical worm 64 is rotatably mounted in the lower compartment 6 and provided with a bevel gear 65 at its outer end which extends into the compartment 5. The shafts 46 carry intermediate pinions 66 which are caused to drive the worm 64 through intermediate shafts 67 carrying at their ends pinions 68 and 69 meshing with the members 65 and 66 respectively. Each worm 64 is surrounded by a nut 70 having a branch 71 in which is journaled a pulley 72. Additional pulleys 73 and 74 (Figures 1 and 2) are mounted at opposite sides of the member 72, and each cable 56 and 57 is passed over one set of pulleys 72, 73 and 74. The worms 64 and 8 are in the ratio of 2 to 1, and the dimensions of the various gears are so determined that the nuts 72 move on the worms 64 to feed or take up the cables at precisely the proper rate. It will be apparent from the positioning of the pinions 66 on the shafts 46 that the worms 64 are turned in opposite directions, but they are oppositely threaded, whereby the nuts 70 ascend and descend together to feed or take up the cable without allowing slack.

A partition 75 (Figures 1 and 9) is provided parallel to one of the ends of the window-frame, forming a compartment 76 for the water hose. This hose, which is designated by the numeral 77 has one end attached to a water coupling 78 inserted in the rear wall 79 of the window casing as

shown in Figure 9. The hose is passed over a pulley 80 suspended from the lower partition 3 and is then passed through the two partitions in parallel relation to the adjacent worm 8 and post 10. Each of the two laps thus formed by carrying the hose in this manner is provided with a loose pulley 81 from which is suspended a weight 82. The hose is then passed around a pulley 83 journaled at one end of the lower track member and finally has its end 22 connected to the nipple 21 as already stated with reference to Figure 21. A waterproof cord 84 is extended through the hose in order to take up the strain caused by its own weight and the members 82.

It is desirable to take the window brush out of contact with the window pane while moving the brush from one part of the pane to another prior to commencing a new stroke of the brush. The apparatus for effecting this function includes cranks 85 secured to the posts 10 and connected by means of links 86 to a rocker arm 87 (Figure 1) on a spindle 88 which is journaled in hangers 89 suspended from the upper partition 2. The spindle 88 has an exterior handle 90 for manipulation. When the spindle is turned to shift the links 86, the cranks 85 are turned and the posts 10 are moved with them. Due to a notch and rib connection 91 (Figure 4) between each post 10 and the corresponding sleeve 13 and collar 16, the fingers 14 and 15 are turned with the posts and shift the tracks and window brush towards or away from the window-pane according to the direction in which the spindle 88 is turned.

The device illustrated in Figure 15 is provided for the purpose of retaining the spindle 88 normally under tension, so that when this tension is released, it will serve to turn the spindle. A rocker arm 92 is pivoted to the window casing and has one end laid upon an expansion spring 93 mounted on a bracket 94. The remaining end of the arm rests on a trip member 95 so that this end may be lifted against the action of the spring. The lower edge of the arm has a notch 96 adapted to receive a lug 97 carried by the spindle 88. A contraction spring 98 has one end secured to the lug, the other end being secured to the window casing as at 99. This device is positioned in such a manner that the contraction of the spring 98 turns the spindle 88 in the direction which moves the brush away from the window-pane. Normally, the lug 97 is positioned in the notch 96 and the spring 98 is expanded when it is desired to move the brush away from the window-pane, the trip 95 is moved to free the rocker 92 from the lug 97, so that the spring 98 is free to contract and turn the spindle 88.

It will be seen from Figure 21 that one end of the cord 84 within the hose 77 is

secured to the nipple 21 by means of a cross pin 100. Due to this arrangement, the weight of the hose and the members 82 serve in aiding the movement of the window brush horizontally towards the end of the window casing in which the hose and weights are mounted. The device for balancing this effect is provided and is illustrated in Figures 2, 12, 13 and 14. It consists of an auxiliary drum 101 loosely mounted on a stub shaft 102 fixedly supported in parallel relation to the drum 53. The latter has a smaller extension 103 in alignment with the drum 101, and a cable 104 has its ends wound on these two members. The stub shaft is loosely surrounded by a ratchet 105 which in turn is surrounded by a coil spring 106. One end of the spring is secured to the ratchet as at 107 and the other end to the drum 101 as indicated by the numeral 108 in Figure 13. Adjacent the ratchet, an arm 109 is secured to the shaft. To the arm is pivoted a pawl 110 which holds the ratchet when the cables are pulled in the direction illustrated in Figure 12, whereby the spring is permitted to be wound.

When the window brush moves towards the hose and weights, the drum 53 must be turned counterclockwise with reference to Figures 1 and 12 in order to take up the cable 57. By means of the cable 104, the auxiliary drum 101 is turned clockwise and the spring 106 is wound. Thus the weight of the hose 77 and members 82, which facilitates turning the drum 53 in counterclockwise direction, also aids in winding the spring. When the window brush is to be moved in the opposite direction, away from the hose and weights, the wound spring facilitates this movement.

The ratchet 105 is stationary, being locked by the pawl 110 in order to provide an anchor for the inner end of the spring 106 at all times. It is used merely as a device for increasing the tension of the spring after the latter has become stretched, in which case the pawl is raised and the ratchet turned.

The rubber strips 31 and 34 are adjusted as to their pressure against the window pane by means of the screws 37. The brush is moved horizontally by means of the cables 56 and 57, and vertically through the worms 8 by actuation of the handle 50 as already described. The stroke of the brush may be either horizontal or vertical as desired. When the brush is to be moved from the end of one stroke to the beginning of the next stroke, it is removed from the window pane by operation of the handle 90 and associated parts in the manner already set forth.

While a specific embodiment of the invention has been illustrated and described,

it is to be understood that various alterations in the details of construction may be made without departing from the spirit of the invention as indicated by the appended 5 claims.

Having thus fully described the invention, what I claim as new and desire to protect by Letters Patent is:—

1. A window washer comprising a pair of parallel worms, nuts threaded on said worms, a track supported by said nut, a brush slidably mounted on the track, cables attached at one end to said brush, and a drum on which the remaining ends of the cables are wound. 10
2. A window washer comprising a pair of parallel worms, nuts threaded on said worms, a track supported by said nut, a brush slidably mounted on the track, cables attached at one end to said brush, a drum on which the remaining ends of the cables are wound, and means for changing the plane of said brush. 15
3. A window washer comprising a pair of parallel worms, guide posts adjacent said worms, nuts threaded on said worms, arms extending from said nuts and loosely surrounding said posts, fingers slidably keyed on said posts and supported by said arms, a track supported by said fingers, a brush slideable on said track, and means for turning said posts. 20
4. A window washer comprising a pair of parallel worms, nuts threaded on said worms, a track supported by said nut, a brush slidably mounted on the track, cables attached at one end to said brush, a drum on which the remaining ends of the cables are wound, a weighted hose connected to said brush, a spring balancing device operatively connected to said drum, and adapted to be wound under the influence of said hose. 25
5. A window washer comprising a pair of parallel worms, nuts threaded on said worms, a track supported by said nut, a brush slid- 30

ably mounted on the track, cables attached at one end to said brush, and a drum on which the remaining ends of the cables are wound, shafts geared to said worms, an operating shaft geared to the first named 50 shafts, another pair of worms operatively connected to the first named shafts, nuts on said second worms, pulleys carried by said nuts, said cables being trained over said pulleys. 55

6. A window washer comprising a pair of parallel worms, nuts threaded on said worms, a track supported by said nut, a brush slidably mounted on the track, cables attached at one end to said brush, and a drum on which the remaining ends of the cables are wound, shafts geared to said worms, an operating shaft geared to the first named 60 shafts, another pair of worms operatively connected to the first named shafts, nuts on said second worms, pulleys carried by said nuts, said cables being trained over said pulleys, and means for changing the plane of said brush. 65

7. A window washer comprising a pair of parallel worms, guide posts adjacent said worms, nuts threaded on said worms, arms extending from said nuts and loosely surrounding said posts, fingers slidably keyed on said posts and supported by said arms, a 70 track supported by said fingers, a brush slideable on said track, means for turning said posts, cables attached at one end to said brush, a drum on which the remaining ends of the cables are wound, shafts geared to said worms, and an operating shaft geared to the first named 75 shafts, another pair of worms operatively connected to the first named shafts, nuts on said second worms, pulleys carried by said nuts, said cables being trained over said pulleys. 80

In witness whereof I have hereunto set my hand.

CAMILLE H. BELLIVEAU.
